UNITED STATES PATENT OFFICE.

OLIVER McCARTHY, OF MERIDEN, CONNECTICUT, ASSIGNOR TO THE
MERIDEN BRITANNIA COMPANY, OF SAME PLACE.

DESIGN FOR A SOCKET-PLATE FOR COFFIN-HANDLES.

SPECIFICATION forming part of Design No. 22,129, dated January 10, 1893.

Application filed September 29, 1892. Serial No. 447,347. Term of patent 7 years.

To all whom it may concern:

Be it known that I, OLIVER McCARTHY, of Meriden, in the county of New Haven and State of Connecticut, have invented a new Design for Socket-Plates for Coffin-Handles; and I do hereby declare the following, when taken in connection with accompanying drawing, to be a full, clear, and exact description of the same, and which said drawing constitutes part of this specification and represents a face view.

This invention relates to a design for the socket-plate for coffin-handles, and consists in the ornamentation as shown in the accompanying illustration.

On the surface of the plate above the socket, is the representation of festoons of flowers appearing to be suspended at their ends from

ribbon knots, and branches with flowers are represented as hanging from the points where the festoons are suspended. Below the socket is a like representation of festoons and dependent flowers suspended from ribbon knots above, and at each edge of the plate is the representation of shell ornaments, as shown in the accompanying illustration.

I claim—

The design for socket-plate for coffin handles as herein shown and described.

In testimony whereof I have signed this specification in the presence of two subscribing witnesses.

OLIVER McCARTHY.
